US00D344264S

United States Patent [19]**D'Aleo et al.****[11] Patent Number: Des. 344,264****[45] Date of Patent: ** Feb. 15, 1994****[54] CONTROL PANEL FOR A LIGHTING CONTROL UNIT**

[75] Inventors: Michael J. D'Aleo, Erwinna; Noel Mayo, Philadelphia; Joel S. Spira, Coopersburg; Craig D. DeBoeser, Allentown; Darryl W. Tucker, Fogelsville; Simo P. Hakkarainen, Bethlehem, all of Pa.

[73] Assignee: Lutron Electronics Co., Inc., Coopersburg, Pa.

[**] Term: 14 Years

[21] Appl. No.: 927,937

[22] Filed: Aug. 7, 1992

CLAIM

The ornamental design for a control panel for a lighting control unit, as shown and described.

DESCRIPTION

FIG. 1 is a front elevational view of a control panel for a lighting control unit according to a first embodiment of the design;

FIG. 2 is a left side elevational view of the embodiment of the design shown in FIG. 1, with part of the environmental structure removed for clarity;

FIG. 3 is a right side elevational view of the embodiment of the design shown in FIGS. 1 and 2, with part of the environmental structure removed for clarity;

FIG. 4 is a top plan view of the embodiment of the design shown in FIG. 1, with part of the environmental structure removed for clarity;

FIG. 5 is a bottom plan view of the embodiment of the design shown in FIG. 1, with part of the environmental structure removed for clarity;

FIG. 6 is a front elevational view of a control panel for a lighting control unit according to a second embodiment of the design;

FIG. 7 is a left side elevational view of the embodiment of the design shown in FIG. 6, with part of the environmental structure removed for clarity;

FIG. 8 is a right side elevational view of the embodiment of the design shown in FIG. 6, with part of the environmental structure removed for clarity;

ment of the design shown in FIGS. 21 and 22, with part of the environmental structure removed for clarity; FIG. 24 is a top plan view of the embodiment of the design shown in FIG. 21, with part of the environmental structure removed for clarity; FIG. 25 is a bottom plan view of the embodiment of the design shown in FIG. 21, with part of the environmental structure removed for clarity; FIG. 26 is a front elevational view of a control panel according to a sixth embodiment of the design; FIG. 27 is a left side elevational view of the embodiment of the design shown in FIG. 26, with part of the environmental structure removed for clarity; FIG. 28 is a right side elevational view of the embodiment of the design shown in FIGS. 26 and 27, with part of the environmental structure removed for clarity; FIG. 29 is a top plan view of the embodiment of the design shown in FIG. 26, with part of the environmental structure removed for clarity; FIG. 30 is a bottom plan view of the embodiment of the design shown in FIGS. 26, with part of the environmental structure removed for clarity; FIG. 31 is a front elevational view of a control panel according to a seventh embodiment of the design; FIG. 32 is a left side elevational view of the embodiment of the design shown in FIG. 31, with part of the environmental structure removed for clarity; FIG. 33 is a right side elevational view of the embodiment of the design shown in FIGS. 31 and 32, with part of the environmental structure removed for clarity; FIG. 34 is a top plan view of the embodiment of the design shown in FIG. 31, with part of the environmental structure removed for clarity; FIG. 35 is a bottom plan view of the embodiment of the design shown in FIG. 31, with part of the environmental structure removed for clarity; FIG. 36 is a front elevational view of a control panel according to an eighth embodiment of the design; FIG. 37 is a left side elevational view of the embodiment of the design shown in FIG. 36, with part of the environmental structure removed for clarity; FIG. 38 is a right side elevational view of the embodiment of the design shown in FIGS. 36 and 37, with part of the environmental structure removed for clarity; FIG. 39 is a top plan view of the embodiment of the

design shown in FIG. 36, with part of the environmental structure removed for clarity; and,
FIG. 40 is a bottom plan view of the embodiment of the design shown in FIG. 36, with part of the environmental structure removed for clarity.
The rear elevational view of each depicted embodiment

has been omitted as it would depict environmental structure only.

The broken line showing is included to show environmental elements only and forms no part of the claimed design.
